UNITED STATES PATENT OFFICE

GEORGE HOCH, OF NEW YORK, N. Y., ASSIGNOR TO STAR CHANDELIER CO., INC., OF NEW YORK, N. Y., A CORPORATION OF NEW YORK

DESIGN FOR AN ELECTRIC WALL BRACKET OR SIMILAR ARTICLE

Application filed August 17, 1929. Serial No. 32,439. Term of patent 3½ years.

To all whom it may concern:

Be it known that I, GEORGE HOCH, a citizen of the United States, residing at 655 Jefferson Place, Bronx, New York, in the county of New York and State of New York, have invented a new, original, and ornamental Design for an Electric Wall Bracket or Similar Article, of which the following is a specification, reference being had to the accompanying drawing, forming part thereof.

The figure is a front elevation of an electric wall bracket, or similar article, showing my new design.

I claim:

The ornamental design for an electric wall bracket, or similar article, as shown.

GEORGE HOCH.
